UNITED STATES PATENT OFFICE.

EDGAR W. SUMMERS, OF PITTSBURGH, PENNSYLVANIA.

DOOR ARRANGEMENT FOR DUMP-CARS.

1,272,871.

Specification of Letters Patent. Patented July 16, 1918.

Application filed February 26, 1918. Serial No. 219,301.

To all whom it may concern:

Be it known that I, EDGAR W. SUMMERS, a resident of Pittsburgh, in the county of Allegheny and State of Pennsylvania, have invented a new and useful Improvement in Door Arrangements for Dump-Cars, of which the following is a specification.

This invention relates to hopper bottom railway cars, and more particularly to cars for handling iron ore and other very heavy material.

The primary object of the invention is to increase the capacity or cubical contents of such a car without increasing the overall length beyond that of present standard ore cars, so that the car will be interchangeable with present standard ore cars and capable of being used in a train made up in part of the old cars and in part of these new cars without interfering with dumping or unloading on the present docks.

This object is secured in part by a change in the shape of the body, but primarily by extending the body downwardly so that its discharge opening is nearer to the track than in standard ore cars and in so mounting the doors that notwithstanding their lower position they will not, when open, extend down so far as to be interfered with or caught by the track.

Practically all the ore docks of this country, particularly those in the Northwest, have the pockets spaced twelve feet between centers, and the standard ore cars are twenty-four feet in length overall, so that when a train of cars is spotted on the track the discharge opening of a car is directly over every alternate pocket. It is desirable and in fact necessary to maintain these dimensions of the ore cars in order that all of the cars of the train may be dumped with a single spotting of the train and in order that the proper chemical mixtures of the ore can be secured in the different pockets of the docks. If the cars were, say thirty-six feet long, it would not be possible to dump all of the cars with a single spotting of the train but it would first be necessary to dump the cars that were centered over pockets and then move the train one direction or the other to spot the cars not initially centered over pockets. Consequently the greatest expedition of unloading is secured by having cars of the standard length of twenty-four feet, thus enabling all cars of the entire train to be dumped with one placing of the

train; and this also facilitates the mixing of the ores in the pockets by enabling the cars containing different grades of ore to be dumped into the proper pockets.

As the docks are already established and to rebuild them would involve a tremendous expense, the ore carrying roads have adopted the 24 feet long overall as standard for ore cars. This limitation in the length of the cars necessarily limits the capacity. The capacity is further limited by the fact that the discharge opening in the bottom of the car cannot be longer than the pocket opening, to avoid spilling ore from a single car into two adjacent pockets and make it impossible to secure the proper chemical mixtures in the different pockets; and by the further fact that the end plates of the car must have a pitch of approximately 50 degrees from the horizontal in order that the sticky ore will discharge by gravity. It is therefore evident that even a longer car, say 36 feet long, would not increase the capacity of the car per lineal foot of track.

The purpose of the present invention is to increase the capacity of such ore cars without increasing their overall lengths or the length of the discharge openings in their bottoms, or reducing slope of the end plates.

This is accomplished in part by giving the car body a greater width and height than is now standard, although the change in height is only slight due to the limitations of the right of way, and in part by making the sloping end sheets of V-shape in cross section so as to secure a slightly increased capacity in this way, and in part by extending the body downwardly to bring the discharge opening closer to the track than has heretofore been the practice. When, however, the body is extended downwardly so that the discharge opening is close to the track the ordinary swinging doors used for closing the discharge opening of cars of this kind will be so low down that when fully open their free edges project below the track and into the pocket and thus prevent moving the car when the doors are open. It has, however, been found that the swinging type of doors are practically indispensable for handling sticky or frozen iron ores. With such material the doors cannot be opened at all if their initial movement is parallel or substantially parallel to their surface contact with a sticky or frozen mass, but when the doors are pivoted this difficulty is obviated

because their initial opening movement is substantially normal to their surface contact with the contents of the car so that they readily fall away from the ore by gravity. 5 But when the doors are mounted upon fixed pivots, as is the practice, it is not possible to extend the car bodies closer to the track nor to increase the width of the doors or the distance between their fixed axes over what is 10 now the practice, as otherwise the lower edges of the doors, when fully open, will extend below the top of the track and thus prevent moving the train when the doors are open, and they must be fully opened in order to get sufficient inclination to permit the 15 sticky ore to run off.

This difficulty is overcome by the present invention by so mounting the doors that in their initial opening movement they pivot 20 around their upper edges in the same manner as ordinary swinging doors, thus permitting them to drop away from the ore body by gravity, thus putting the door in motion so that the inertia of this motion 25 and the wedging action of the falling mass of ore from above will prevent sticking and stopping the movement of the doors; and after this initial movement, said doors have a bodily swinging movement to increase their 30 inclinations and enlarge the discharge opening without further materially lowering their centers of gravity, thus enabling the doors to move to full open position and still clear the track.

35 In the accompanying drawings, in which one embodiment of the invention is illustrated, Figure 1 is in part a side elevation and in part a central longitudinal section through a car embodying the invention; 40 Fig. 2 is in part a plan view and in part a horizontal section through the body of the car illustrated in Fig. 1; Fig. 3 is in part an end elevation and in part a vertical transverse section between the end and bolster of 45 the car; Fig. 4 is a central transverse vertical section through the car; Fig. 5 is a diagrammatic view on an enlarged scale showing the doors and their mounting and actuating mechanism and illustrating the movement of 50 the doors when opening; Fig. 6 is a plan view of the door actuating mechanism; Fig. 7 is a detail view showing a portion of the door actuating mechanism in elevation, looking from the end toward the center of the 55 car; Fig. 8 is a side elevation of the mechanism shown in Fig. 7; and Fig. 9 is a side elevation of the locking pawl and dumping mechanism shown in Fig. 7.

The car body illustrated is of the general 60 design of hopper bottom cars used in the ore carrying trade. It comprises the vertical side walls 10, end walls, 11, sloping end plates 12, and sloping side plates 13 extending down to the center discharge opening, which is of a length nearly equal to the 65

clear distance between the inner truck wheels and of a width materially greater than the track, as is apparent from Figs. 3 and 4. This body is carried by the usual trucks and has horizontal buffer columns 70 or girders 14, bolsters 15 and longitudinal draft sills 16, and other frame members which need not be described in detail. The end plates 12 are inclined at an angle of approximately 50 degrees from the horizontal so as to insure the sticky ore being discharged by gravity. Furthermore, these end plates not only slope from the end wall 11 to the discharge opening, but also slope from the sides of the car toward its longitudinal center line. As a consequence, some increase in capacity is obtained in this way and also the ends of the door openings (the doors being inclined from the sides to the center of the car) are straight lines, giving 80 a discharge opening of regular form.

As a further means for increasing the capacity the car body is as wide as the clearances along the right of way permit, and this results in a discharge opening in the 90 bottom of maximum width.

An increase in capacity is further obtained by extending the body downwardly toward the track lower than has heretofore been the practice, and this has enabled the car body 95 to be also made higher, because the downwardly projection of the body maintains the center of gravity at a safe height. The net result is that the car has a capacity nearly 100 50 per cent. greater than standard ore cars of the same length as heretofore constructed, and, further, has a very wide discharge opening and one which is of regular shape, that is, straight at the ends as well as at the sides.

The discharge opening is closed by means 105 of two doors 18, which lie in an inclined position, sloping from the sides of the car to and meeting at its longitudinal center line, and which are hinged to the body at their upper outer edges. In order to permit these low 110 hung doors to swing fully to open position without being interfered with by the track, they are so mounted that at the beginning of their opening movement they pivot about their upper edges and allow the lower edges 115 to drop away from the load, but after such initial movement they move bodily to increase their inclination and the size of the discharge opening but without materially further lowering their centers of gravity. This can be accomplished in various ways. 120 As shown, the upper edges of the doors are hung on short links 20, pivotally connected to the edges of the doors at 21 and to the car body at 22, the latter connection being 125 to brackets secured to the under side of the horizontal girders 14; while their lower edges are suspended by longer links 23 pivotally secured to the car body at 24, such as being pivoted to brackets 25 secured to the 130

car framing beyond the ends of the discharge opening, while their lower ends have both a pivotal and lost motion connection with the doors near their lower edges, this latter connection being secured by providing the links with slots 26, which receive pivot pins 27 mounted in castings 28 secured in the ends of V-shaped pressed stiffening girders 29, secured to the lower faces of the doors near their inner edges. As a consequence of this mounting, when the door holding means is released, the inner ends of the doors drop freely, due to the slot and pin connections 26 and 27, and pivot around the pivots 21 substantially as though the latter were fixed pivots. This movement continues until the lost motion connection at 26 and 27 is taken up in which condition the doors have assumed the dotted line position 30, Fig. 5. The inertia imparted to the doors by this movement, as well as the wedging action of the ore falling down onto the doors and through the gap between the same, forces the doors outwardly in a bodily 20 swinging movement at their outer edges around the pivots 22 as a center and at their inner edges around the pivots 24 as a center. This swinging movement moves the doors outwardly to increase the width of 30 the discharge opening and also to increase the inclination of the doors (due to the fact that the links 23 are longer than the links 20), but when in their final positions, their lower edges are at substantially the same 35 level as after the initial pivotal movement. The final positions of these doors is indicated by the dotted lines 31, Fig. 5. As a consequence, the doors move to fully open position and assume an inclination sufficient 40 to insure the discharge of the sticky mass by gravity, and at the same time have their lower edges sufficiently high to clear the track, so that there is no danger of injuring the doors should the engineer start the train 45 before the doors are closed. Various other manners of mounting the doors to secure this result can be devised.

The means for actuating the doors may be of various kinds but that illustrated in the drawings is efficient. As shown, there is secured to the ends of each door, outside of the discharge opening, links 32 having their inner ends pivotally connected to the pins 27, and having at their outer ends curved 55 sections or members 33 which are connected to the wrist pins 34 carried by the outer ends of crank arms 35 secured to the longitudinal shafts 36 which are mounted in suitable bearings underneath the sides of the car. Obviously when the shafts 36 are rotated from the position shown in full lines in Fig. 5, the wrist pins 34 describe arcs of circles as shown in Fig. 5, and permit the doors to open, whereas, when the shafts are rotated 60 in the opposite direction, the crank arms 35

pull upon the connecting links or rods 32 and draw the doors inwardly to their closed positions. The parts are so designed that the cranks 35 carry the wrist pins 34 to such a position that they are slightly beyond a straight line connecting the centers to shafts 36 and pins 27 (the curves in the members 33 permit the cranks to assume this position) and consequently, the load on the doors tends to hold them in their closed positions. 75

This closing means is very efficient because the links 32 are pulling substantially normal to the planes of the doors when in open position and consequently the doors can be closed with a minimum amount of power. 80

Apron plates 38 are attached to the sloping end floor plates 12 at each end of the door opening on both sides of the car to form with the doors, when in open position, chutes or slides to confine the ore and prevent it from spilling over into an adjacent pocket of the dock. 85

The longitudinal shafts 36 are extended toward one end of the car and are connected by beveled gears 40 to a transverse shaft 41 mounted on the car frame underneath the sloping end plates, so that thereby both longitudinal shafts 36 are simultaneously actuated. The shaft 41 is actuated by means of a second transverse shaft 42 whose ends 90 project beyond the car sides and are shaped to receive suitable actuating means, such as a crank. The connection between the shafts 41 and 42 is such that the doors can be both opened and closed by a rotation of 100 the shaft 42 in one direction. The mechanism for accomplishing this and for locking the doors in closed position is shown in Figs. 6, 7, 8 and 9. As here shown, the shaft 41 has keyed thereto a gear 44 which meshes 105 with a pinion 45 loose on the shaft 42. Keyed to but slidable on the shaft 42 is a clutch member 46 adapted in one direction to lock the pinion 45 to the shaft 42, in its intermediate position to be entirely disengaged on both sides, and in its opposite position to lock to the shaft 42 a member 47, which is normally loose on shaft 42 and which is provided with a detent or dog 48 115 engaging a ratchet disk 49 fast on the shaft 42. The member 47 is also provided with an arm 50 which is connected by means of a curved disk 51 to the outer end of an arm 52 pivoted on the shaft 41. The disk 49 is provided with a lateral shoulder 53 which cooperates with the arm 52 for opening the doors. 120

Assuming that the doors are closed and it is desired to open the same, the clutch 46 is shifted to engage the member 47 and then by turning the shaft 42 (in a clockwise direction, Fig. 9) the detent 48 is disengaged from the ratchet teeth on the disk 49, and the arm 50, through the link 51, rocks the 125

arm 52 upwardly, causing the same to engage the shoulder 53 on the disk 49 and rotating the latter also clockwise. Since the disk 49 is fast on the shaft 41, this imparts 5 rotary movement to the shafts 36 so as to move their crank arms 35 from the full line position shown in Fig. 5. As soon as the center line of the links 33 pass beyond the center of the shafts 36, the weight of the 10 load on the doors and of the doors themselves is sufficient to cause the doors to move fully to their open position so that the mechanism described serves primarily merely to initiate the opening movement. When it is 15 desired to close the doors clutch member 46 is moved in the opposite direction to engage the pinion 45 and lock the same to shaft 42, and by merely rotating the shaft 42 in the same direction in which it was rotated to 20 open the doors, rotary movement is imparted by gear 44 to shaft 41 and thence to shafts 36 which are now rotated in the opposite direction to pull on the links 32 and close the doors. When the clutch 46 is dis- 25 engaged from the member 47, the link 51 and arm 52 drop back by gravity, assisted by spring 54, to normal position and during the closing of the doors the detent 48 merely clicks over the ratchet teeth on the disk 49, 30 and when the doors are fully closed said detent engages the ratchet teeth to positively lock the doors in closed position, although generally very little strain is placed on these locking means because, as already stated, the 35 cranks 35 and centerline of links 32 are beyond the center of shaft 36, so that the weight of the doors themselves automatically tends to hold them in closed position.

The clutch member 46 is shifted by means 40 of a bell crank lever 55 pivotally mounted at 56 (Fig. 7) and having one arm forked and engaging a groove in the clutch member 46 and its other arm perforated and engaged by a rod 57 slidable through said perfora- 45 tion, but engaging the arms by means of cushioning springs 58 on each side thereof and which arm is connected to a crank 59 formed in a transverse operating rod 60 mounted in suitable bearings 61 on the car 50 frame and extending to both sides of the car and there provided with operating handles or cranks 62. By rotating the shaft 60 in one direction, the clutch member 46 is caused to engage the member 47 for opening the 55 doors and by rotating said shaft 60 in the opposite direction said clutch member is caused to engage the pinion 45 for rotating the shafts 36 in the opposite direction to close the doors. The cushioning springs 58 60 are provided in order that, in case the clutch faces on the pinion 45 and member 47 are not in position to receive the clutching face on the member 46 when the shaft 60 is rotated, one or the other of said springs will 65 be put under compression so that as soon

as the shaft 42 is rotated, the springs will push the clutch member 46 into locking engagement with the pinion 45, or member 47 as soon as the clutching faces have been brought into alignment. 70

By the mechanism described, the doors can be actuated from either side of the car and both the opening and the closing movement is effected by rotation of the shaft 42 always in the same direction. 75

The railway car illustrated and described has a much greater capacity than any ore car now in use and at the same time is not increased in its overall length, so that it is entirely interchangeable with cars already 80 built and in use, and preserves all of the advantages of the standard length of ore cars as hereinbefore described. 80

What I claim is:—

1. An inclined door for bottom discharge 85 dump cars having independent mountings at its upper and lower edges arranged to allow the door at the beginning of its opening movement to pivot about its upper edge and allow the lower edge to drop away from the load and after such initial movement to move bodily outward without materially lowering its center of gravity, and door actuating means, substantially as and for the purpose described. 90

2. An inclined door for bottom discharge dump cars, and suspending means at both edges thereof having pivotal connection with both the door and the car body, the suspending means at the lower edge of the 100 door having a lost motion connection therewith, whereby at the beginning of the opening movement the door pivots about its upper edge and its lower edge drops away from the load and thereafter has a bodily swinging movement, and door actuating means, substantially as and for the purpose described. 105

3. An inclined door for bottom discharge 110 dump cars, and suspending means at both edges of the door having pivotal connections with both the door and the body or frame of the car, the suspending means at the lower edge having a lost motion connection therewith and being longer than the suspending means at the upper edge of the door, whereby the door in its initial movement pivots about its upper edge and the lower edge drops away from the load and thereafter has a bodily swinging movement to increase its 115 inclination and enlarge the discharge opening, and door actuating means, substantially as and for the purpose described.

4. In a bottom discharge railway dump 120 car, a pair of longitudinally hung doors in the bottom thereof meeting on the longitudinal center line of the car in their closed position, independent mountings for the upper and lower edges of said doors so arranged that the initial opening movement of said 125 130

doors is about fixed points at or near their upper edges and the concluding opening movement is a substantially bodily movement sidewise, and door actuating means, substantially as and for the purpose described.

5. In a bottom discharge railway dump car, a pair of longitudinally hung doors in the bottom thereof meeting on the longitudinal center line of the car when closed, independent suspending means for the upper and lower edges of said doors and having pivotal connection with both the doors and the car body, the suspending means at 10 the lower edges of the doors having lost motion connections therewith, whereby at the beginning of the opening movement the doors pivot about fixed axes at or near their upper edges and thereafter have a substantially bodily movement sidewise, and door 15 actuating means, substantially as and for the purpose described.

6. In a bottom discharge dump car, a pair of longitudinally hung doors in the bottom 20 thereof meeting at the longitudinal center line of the car when closed, independent suspending means for the upper and lower edges of the doors having pivotal connections with both the doors and the body or 25 frame of the car, the suspending means at the lower edges of the doors having a lost motion connection therewith and being longer than the suspending means at the upper edges of the doors, whereby the initial 30 opening movement of said doors is about fixed axes at or near their upper edges and the concluding opening movement is a substantially bodily movement sidewise, and door 35 actuating means, substantially as and for the purpose described.

7. In a bottom discharge railway dump car, a pair of longitudinally hung doors in the bottom thereof meeting on the longitudinal center line of the car when closed, actuating means for said doors comprising a 40

longitudinal shaft mounted on each side of the car at the side of the discharge opening, means directly connecting each of said shafts to the door on the opposite side of the car, and operating means for said shafts. 50

8. In a bottom discharge railway dump car, a pair of longitudinally hung doors in the bottom thereof meeting on the longitudinal center line of the car when closed, actuating means for said doors comprising a longitudinal shaft mounted at each side of the discharge opening, operative connections between said shafts and the doors, a transverse shaft connecting both of said longitudinal shafts, and actuating mechanism for said transverse shaft arranged to operate the same to both open and close the doors by movement of said actuating means in the same direction and to lock the doors in closed position. 55 60 65

9. A hopper car body provided with a central bottom discharge opening arranged low and near to the track and provided with end plates sloping from the end of the body to said opening and being of V-form transversely of the car, thereby providing a rectangular discharge opening, oppositely swinging inclined doors longitudinally pivoted at the sides of said discharge opening and inclining downwardly and meeting at the longitudinal center line of the car when closed and so mounted that at the beginning of their opening movements they pivot about their upper edges to allow their lower edges to drop away from the load and after such initial pivotal movement they move bodily to increase their inclinations and increase the door opening without materially lowering their centers of gravity, and door actuating means. 70 75 80 85

In testimony whereof, I have hereunto set my hand.

EDGAR W. SUMMERS.
